UNITED STATES PATENT OFFICE.

JOSEPH NOCHECK, OF CHEVIOT, OHIO.

APPARATUS FOR BACKING UP ELECTROTYPE.

1,183,105.

Specification of Letters Patent.

Patented May 16, 1916.

Application filed June 23, 1913. Serial No. 775,231.

To all whom it may concern:

Be it known that I, JOSEPH NOCHECK, a citizen of the United States, and a resident of Cheviot, Hamilton county, State of Ohio, have invented a certain new and useful Apparatus for Backing Up Electrotype; and I do declare the following to be a clear, full, and exact description of the invention, attention being called to the two sheets of drawings, which accompany this application and form a part thereof.

This invention relates to a machine for backing-up electrolytically produced printing-faces for printing type-matter, illustrations etc. These faces, the result of the electrotype-process, are metallic shells, copper being generally used, which on account of their limited thickness require strengthening to render them available for use in printing. This is done by what is called "backing-up" and consists of providing these shells with a back formed of metal for which a suitable alloy or so-called type-metal is generally used. The usual procedure for forming this backing is by placing the metal-shells face down upon the bottom of a flat pan, after which the metal to be used for backing them, it being in molten condition, is poured into the pan, generally by means of a hand-ladle, and floated over the back of the shell, so as to closely adjust itself against the same and to fill into the many recesses which make up the type-face. The pans are of a depth to permit them to receive sufficient of this metal to cause formation of backing of proper thickness, this thickness being approximately one fourth of an inch more or less. The connection between the shell and this metal whereby it is backed, is substantially a soldering connection, formed analogous to a soldering joint, and preliminary treatment by deoxidizing and fluxing must be had, for which purpose, the backs of the shells are first acid-treated and tinned. The backed-up shells after being cooled are removed from the pans, planed off and leveled, trimmed around their edges and mounted upon wooden bases after which they are ready for use in the printing press.

The subject of this invention concerns an apparatus used for backing-up electrotype-shells in the manner outlined and whereby more particularly pouring of the metal by hand-ladle is dispensed with which on ac-

count of the heat is exhaustive and toilsome work.

The invention consists of such an apparatus, constructed as hereinafter described and pointed out in the claims, and as illustrated in the accompanying two sheets of drawings, in which:—

Figure 1, shows a top-view of the apparatus. Figs. 2 and 3, show similar views at reduced scale with operative parts appearing in different positions. Fig. 4, is a side-elevation of the device, partly shown in section taken on line 4—4, indicated in Fig. 1. Fig. 5, shows the sectional portion of the preceding figure extended to adjacent parts, all being shown on enlarged scale. Fig. 6, shows an elevation of certain parts as viewed in a plan and direction indicated at 6—6 in Fig. 4.

The apparatus consists essentially of a rotary carrier adapted to support the pans which receive the shells to be backed-up. In connection there are means provided for supplying heat necessary to apply the required tinning to the back of the shells and to prepare for fluxing the backing metal. Further there are means to discharge molten metal into each pan and in proper quantity to float over the back of the shells to sufficient depth to make backing of proper thickness, this discharge being by preference automatic and under adjustable control. Finally there are means to apply a cooling medium to cool the metal with sufficient rapidity to permit removal from the pans of the backed shells and replacing of other shells to be backed without interrupting the movement of the carrier.

The carrier consists of a circular frame A, supported for rotation in a horizontal position at the upper end of a standard 10, and of brackets a, which in desirable numbers extend radially from the periphery of this frame. These brackets serve for supporting the pans B, which receive the shells C to be backed and the metal used for the purpose. The carrier-frame with the brackets is rotated by suitable means at a moderate speed appropriate for operation. These rotating means consist of an internal gear 11, provided on frame A and engaged by a pinion 12 at the upper end of an upright shaft 13. This latter is actuated by suitable motive power as for instance by an electric motor 14 and by suitable inter-

venient transmitting gears arranged to obtain proper speed. The discharge of the molten metal is timed so as to occur only while a pan passes in proper position to receive it. The quantity discharged at that time is of course so apportioned that the metal rises above the shells sufficiently to produce backing of the desired thickness. The same quantity is released at each discharge inasmuch as the pans are all of the same size irrespective of any variation in the size of the type-shells, the size of the pans being so as to be capable of receiving the largest shells which may be made. No waste results however because the surplus metal may be re-melted after having been cut off even with the edges of the shells when the resultant type-plates are trimmed to size.

In order to obtain the necessary quantum of metal in the limited time during which discharge is available, metal is released simultaneously from a number of openings above a pan. The advantage of a discharge of this character as against one from a single, but larger, outlet is that it prevents buckling of the shells, or curling up at their edges, which would result from the limited contact of a concentrated discharge of metal, an objectionable effect connected with the pouring of the metal when the hand-ladle is used. For such purpose I provide a discharge-head D, which has a number of outlets *d* arranged in a line substantially radial to the carrier, the length of the row of outlets being arranged with respect to the length, radially considered, of the pans, and the row being so positioned as to be above the path of the pans and entirely within the same. See Fig. 5.

Discharge from the head is controlled by controlling the supply thereto and is obtained by means of a valve 15. This valve might be actuated manually, but by preference it is actuated by means operating automatically and in a manner that discharge of metal starts as soon as a pan has passed fairly below the discharge-head and is caused to stop again before the same pan has passed out from below the discharge-head. Inasmuch as variation in the weight of the body of molten metal lying back of the discharge-head has a tendency to modify discharge from this latter quantitatively and in a manner affecting the thickness of the backing to be produced, it is desirable to arrange for the maintenance of a constant body of molten metal from which the discharge-head is supplied. For this reason and instead of connecting the discharge-head directly to the melting-pot E, I connect it to an interposed pot F, which receives the metal in molten condition from the melting-pot and holds it in readiness for supplying the discharge-head. A con-

duit *e* connects the melting-pot with this supply-pot and a constant body of metal is maintained in this latter by means of an automatically actuated valve 17 which controls passage through conduit *e*. This provides also metal clear of dross which latter remains in pot E. The actuation of valve 17 is preferably by means of a ball-float 18 which rises and falls with the level of the metal in pot F and by its obvious connection and operation actuates valve 17 in the desired manner.

G indicates a suitable furnace for supplying heat below melting-pot E.

Valve 15 is actuated to cause flow of metal from the discharge-head into the pans which pass below it, by cams 19, which move with the carrier, one being provided for each pan. These cams pass under and lift a rod 21 and an arm 22 connected to it to which valve 15 is connected by a stem 23. Prompt closing-action of the valve is had by means of a weight 24. Its position within the pot which contains the molten metal prevents possible interference by congealed metal. Rod 21 is sustained by a braced bracket 25 on which it moves. Removal from pans B of the shells, after they have been backed, can of course not occur until the metal has congealed to a consistency sufficiently rigid to permit this to be done.

The placing of shells to be backed must occur so far in advance before reaching the discharge-head as to permit application of heat necessary for tinning them, which tinning must have been completed before the shells arrive below the discharge-head where they receive the backing metal. The location of these points where the shells are handled in this manner depends on special conditions and arrangements, determined by the size of the carrier, the number of pans carried thereby and the speed of movement.

For present purposes and conditions it is assumed that the removal of the backed shells from the pans and the replacing of other shells to be backed takes place at a point approximately opposite the discharge-head. These shells, while passing from this point and before reaching the discharge head, are tinned on their upturned backs as before stated, to prepare them for receiving the backing-metal. A convenient way for applying the tin required for the purpose is by using it in form of foil which is placed upon the back of the shells, they having been subjected first to treatment by acid or soldering fluid. Sufficient heat is then applied to bring the tin to the melting point so as to cover the back of the shells. This application of heat is preferably from below and against the underside of the pans. Gas or electricity are the most convenient sources for obtaining this heat.

Gas is the fuel presumed to be used here

by means of suitable burners. These latter are positioned so as to be below the path through which the pans move, thus subjecting them to the heat generated. When economy in the use of fuel is a desideratum, the supply of gas to the burners may be controlled in a manner that full supply is had only while a pan passes over a burner. This is done by means moving with the carrier and acting upon valves which control the supply to the burners in a manner to alternately increase and reduce this supply. A preferable arrangement is to provide a set of burners adapted to apply heat simultaneously to several pans and while moving with the carrier for a part of its rotation, after which the burners are automatically returned to an initial position to be picked up again, they being properly spaced and positioned so that each burner moves with a pan and below the same. Heat is thus used in a most direct way and without appreciable waste of it.

In the apparatus shown I apply heat simultaneously against the underside of three pans by means of three burners 26, mounted upon a supply-pipe 27, and supported by means of bracket-arms 28, projecting from a bearing 29, which is mounted on standard 10. The connection to this latter is in a manner permitting rotation of this burner-structure on the standard. Suitable mechanism is used comprising for instance trips 31 which, yieldingly connected, depend from each bracket 28 and are adapted to engage a projection 32, attached to the burner-structure and located so as to extend into the path of said trips as they travel with the carrier. The burner-structure is thus caused to move with the carrier which movement continues until in due time the trips encounter a cam 33, held in a stationary position. This contact causes the burner-structure to become disengaged from the carrier each time a trip engages the cam, and permits it to return to its starting position. This return occurs immediately before a pan passes below the discharge-head and the motion of the burner-structure in reversed direction is so limited as to terminate in a position where each burner is again below a pan. Compare Figs. 2 and 3, the first figure showing positions of the parts before and the other immediately after this change of positions. From this position the burner-structure is presently picked up again by another trip, the mechanism as used being arranged that this occurs when the burner-structure has passed back a distance approximately equal to the distance between two pans. In other words, for each of the advancing pans which passes away from the burners and under the discharge-head, another pan is added to those which pass above the burners to be heated by them. See Fig. 3. The move-

ment in reversed direction of the burner-structure is effected by suitable means as for instance by the action of a weight 34. It is connected to the burner-structure by means of a cable 35, which passes over a guide-roller. An elastic buffer device 36 is provided which cushions the weight before it has reached the limit of its fall. A marginal flange 37, provided with vent-openings and integral protuberances 38 on the underside of the pans favor retention of heat until the pans come around again where they pass above the burners. From this point the heat is then readily raised to the required degree and in the time available before the pans reach the discharge-head. Gas is supplied to burner-supply-pipe 27, in a suitable manner as for instance by a flexible connection 39, coupled to a feed-pipe 41. The same pipe may supply gas to two burners 42, one provided on each side of the discharge-head and below supply-pot F. The object of these burners is to maintain the liquidity of the metal to insure its free flow.

Congealing of the discharged metal, to permit removal of the shells after being backed is hastened by an air blast directed against them from a blast head 43, supplied by a blast-pipe 44. Additional blast-heads 45 are provided which discharge against the pans from below. They might be arranged in a stationary position, but by preference they are arranged and spaced in a manner similar to burners 26, that is, they travel with the pans and below them. I have shown three of these blast-heads supplied from a blast-pipe 46 which is supported upon arms 47, connected to bearing 29, which supports also bracket arms 28 of the burner structure so that these blast-heads move with the burner structure and are actuated and controlled as to their movement by the same trip-mechanism.

Whenever a pan has received its charge of metal and passes away from the discharge-head, the before described motion of the burner-structure causes also the first of the blast-heads, they moving with this structure, to pass below this pan, after which all the lower blast-heads, each below a pan, move with them. Observe Fig. 3. Blast-pipe 44 leads through standard 10 to a conventional blower 48 which may be actuated by motor 14. Blast-pipe 46 is connected to blast-pipe 44 by means of a yielding connection as for instance by fitting one pipe loosely over the other one, to permit it to slide, sufficient lap being provided to maintain the connection.

Summarized, the various steps of the operation are as follows: The shells are placed face down into pans and pass on with them to a point where they receive the backing-metal from a pouring-device. If the char-

acter of the metal used is such as to require tinning of the shells, this is done while they pass to the pouring-device and so as to be completed when they reach this device.

5 In this case the shells are first acid-treated and the tin in convenient shape, as for instance foil, is placed. Heat is applied in suitable form, to cause melting of the tin. This is done by burners positioned below 10 the pans and accompanying them for part of their travel. The tinning of each shell is complete as they pass under the discharge-head of the pouring-device where they receive the backing-metal. The discharge of this metal is effected by cams 19 which act upon valve 15 in the manner described. At that time the burners which have moved with the pans slip back and the burner under that particular pan which is 15 receiving metal does not further follow it. Passed beyond the discharge-head, the backed shells are subjected to an air-blast, to permit their removal in due time. The proper quantity of metal is discharged each 20 time into each pan and this discharge is under perfect control as to time and quantity by actuation accordingly of valve 15 which admits the metal to the discharge-head. Such actuation is obtained by positioning cams 19 correspondingly and by arranging their length and height upon which factors the lift of valve 15 and the duration 25 of its opening depends. Various expeditencies for exact adjustment of this control suggest themselves readily. The interposition of supply-pot F, between the discharge-head and the melting-pot insures clean metal, free from dross which remains in the melting-pot where it floats to the top.

30 As a result, spongy plates are avoided and clean casts are obtained of solid metal free from cavities and bubbles.

The work of the tender is not as onerous as when dipping and pouring the metal 45 with the hand-ladle, since he handles no molten metal at all and his position is remote from the furnace and from the pouring-device where the metal is the hottest.

Having described my invention, I claim as 50 new:

1. In an apparatus for backing-up shells which form printing-faces, the combination of a discharge-head having normally open outlet openings, pans adapted to receive shells to be backed-up, a movable carrier whereby the pans are caused to pass below the openings of the discharge-head, a container for molten-metal in normally closed communication with the discharge-head, means to control this communication and devices to actuate these means so as to admit metal to the discharge-head only when a pan passes below the outlet openings thereof.

65 2. In an apparatus for backing-up shells which form printing-faces, the combina-

tion of a melting-pot, a container in communication therewith and adapted to receive molten metal therefrom, a discharge outlet for this container, pans adapted to receive shells to be backed-up and the metal 70 for it from the discharge outlet, means to control the flow of this metal to the pans and means to automatically control the flow of the metal from the melting pot to the container to maintain a constant supply in 75 this latter.

3. In an apparatus for backing-up shells which form printing-faces, the combination of pans adapted to receive shells to be backed-up, a carrier to move them, an elongated discharge-head approximately equal to the length of the pans located above the path of the pans and provided with outlet openings arranged in a line disposed at right angles to the direction in which the 80 carrier moves whereby a distributed discharge of metal is effected and means to permit discharge from these openings only when a pan passes below them.

4. In an apparatus for backing-up shells 90 which form printing-faces, the combination of pans adapted to receive shells to be backed-up and the metal required therefor, a carrier whereby they are moved, an automatically controlled pouring-device provided above the path of the pans wherefrom the metal is supplied to the pans and means to maintain the supply of molten metal for 95 this pouring-device at a constant level.

5. In an apparatus for backing-up shells 100 forming printing-faces, with a metal which requires preliminary tinning of the shells, the combination of pans adapted to receive those shells and the material required for 105 tinning them, a carrier whereby the pans are moved to a point where they receive the molten backing-metal and means to apply heat to these pans and to the shells therein to effect the tinning of them before they receive the backing-metal.

6. In an apparatus for backing-up shells forming printing-faces, with a metal which requires preliminary tinning of the shells, the combination of pans adapted to receive these shells and the material required for 115 tinning them, a carrier whereby the pans are moved to a point where they receive the molten backing-metal, burners movably supported below pans carrying shells to be 120 tinned and adapted to apply heat for the purpose while temporarily traveling with these pans toward the point where they receive the backing-metal and means to cause the burners to recede from under pans which contain shells the tinning of which 125 is completed and to return to be below pans advancing with shells requiring tinning.

7. In an apparatus for backing-up shells which form printing-faces, the combination of pans adapted to receive shells to be 130

backed-up and the metal required therefor, a pouring-device which contains this metal, a carrier to move the pans with the shells past this pouring-device and means to cool 5 the backed-up shells in the pans after they have passed this device and before they are removed from said pans.

8. In an apparatus for backing-up shells forming printing-faces, with a metal which 10 requires preliminary tinning of the shells, the combination of pans adapted to receive these shells and the material required for tinning them, a carrier whereby the pans are moved to a point where they receive the 15 molten backing-metal, means to apply heat to these pans and to the shells therein to effect the tinning of them before they receive the backing-metal and means to cool the shells after they have received the backing 20 metal.

9. In an apparatus for backing-up shells forming printing faces, the combination of pans adapted to receive shells to be backed-up and the metal therefor, a carrier whereby 25 they are moved, a pouring-device provided above the path of the pans and means to subject the backed-up shells to the action of an air-blast delivered upon the backing after they have passed the pouring-device.

30 10. In an apparatus for backing-up shells forming printing faces, the combination of pans adapted to receive shells to be backed-up and the metal therefor, a carrier whereby they are moved, a pouring-device provided 35 above the path of the pans, movably supported blast-heads to apply air to cool the backed-up shells, while temporarily moving with them after they have passed the pouring-device, and means to cause these 40 blast-heads to return and to move under the pans advancing from the pouring-device with backed-up shells.

11. A pan adapted to hold shells which 45 form printing-faces while being backed-up with a metal requiring preliminary tinning and which is effected by heat applied to the underside of said pan, said underside being provided with heat-retaining means in form of a marginal, downwardly projecting 50 flange and downwardly projecting protuberances.

12. In an apparatus for backing-up shells

forming printing-faces, the combination of 55 pans adapted to receive shells to be backed-up and the metal therefor, a carrier whereby they are moved, a pouring-device provided above the path of the pans, a blast-head also provided above the path of the pans and spaced from the pouring-device and means to supply air to the blast-head. 60

13. In an apparatus for backing-up shells which contain printing-faces, the combination of a circular frame, a central support on which it is carried for rotation, brackets extending radially from the periphery of 65 this frame outwardly, pans supported on these brackets in permanent, horizontal position and adapted to receive the shells to be backed-up and a pouring-device provided above the path of the pans. 70

14. In an apparatus for backing up electrotype shells, a melting pot for melting the backing metal, a backing pan, a pipe or duct forming a communication between said melting pot and backing pan, and means for 75 spreading the molten metal backing as it is delivered to the backing pan from the melting pot, substantially as described.

15. In an apparatus for backing up shells forming printing faces the combination of 80 a pan adapted to receive a shell to be backed and the metal required therefor, means adapted to discharge this metal in molten condition and in a manner so as to spread the same over the back of the shell while 85 delivering it into the pan, and a container for this molten metal in communication with said means.

16. In an apparatus for backing up shells forming printing faces, the combination of 90 a pan adapted to receive a shell to be backed and the metal required therefor, a container for the molten metal and a discharge head in communication with this container and adapted to discharge the molten metal into 95 the pan and in a manner that the metal is delivered over an extended area of the shell.

In testimony whereof, I hereunto affix my signature in the presence of two witnesses. 100

JOSEPH NOCHECK.
